(57) **CLAIM**

The ornamental design for a medical laser drive module, as shown and described.

DESCRIPTION

FIG. 1 is a perspective view of one embodiment of a medical laser drive module showing a user screen in an upright position;

FIG. 2 a front side view thereof;

FIG. 3 is a back side view thereof;

FIG. 4 is a right side view thereof;

FIG. 5 is a left side view thereof;

FIG. 6 is a top side view thereof; and

FIG. 7 is a bottom side view thereof.

FIG. 8 is a perspective view of one embodiment of a medical laser drive module showing a user screen in a stowed position;

FIG. 9 a front side view thereof;

FIG. 10 is a back side view thereof;

FIG. 11 is a right side view thereof;

FIG. 12 is a left side view thereof;

FIG. 13 is a top side view thereof; and,

FIG. 14 is a bottom side view thereof.

In FIGS. 1 through 14 the broken lines show portions of the design for a medical laser drive module that form no part of the claimed design.
